UNITED STATES PATENT OFFICE.

JOHN AENIS, OF CLEVELAND, OHIO.

OIL-STOVE.

SPECIFICATION forming part of Letters Patent No. 340,653, dated April 27, 1886.

Application filed August 29, 1885. Serial No. 175,624. (No model.)

To all whom it may concern:

Be it known that I, JOHN AENIS, of Cleveland, in the county of Cuyahoga and State of Ohio, have invented certain new and useful 5 Improvements in Oil-Stoves, of which the following is a specification.

The invention relates to oil-stoves; and it consists of the combination, with an oil-stove having wick-tubes, of a combustion-chamber 10 located above the wick-tubes, which are inclosed in a casing the interior of which communicates with the said combustion-chamber by suitable openings, and the said combustion-chamber provided with a series of rods arranged in rows across the interior thereof, 15 whereby the gases from the wicks and atmospheric air admitted therein commingle with and produce perfect combustion.

The invention is illustrated in the accompanying drawings, in which Figure 1 is a vertical section of a stove-lamp having two wick-tubes, and a combustion-chamber having double rows of rods. Fig. 2 is a like vertical section of a single wick-tube with one double 25 row of rods. Fig. 3 is a transverse vertical section of the same. Fig. 4 is a top or plan view of the double-row lamp.

A is the body or fount of the stove, to the top of which is attached a neck, B, in which 30 are contained the wick-tubes and wick-wheel raising and lowering mechanism. To the said neck is attached a metal chamber, C, in which are placed perpendicular rows of rods c. These rods are arranged horizontally a little space 35 apart and in double rows, forming a double column, between which the flames from the wick rises. Perforations e are provided in the top of the neck and at each side of the wick-

top for the admission of air. The neck is also provided with openings b in its lower part for 40 the admission of air. Over the top of the chimney is placed a plate, D, a short distance above the top opening in said combustion-chamber, which opening is contracted to the space between the rods, as seen in Fig. 2. 45

In Fig. 1, where there are two wicks, the fount is provided with a central tube, a, for the admission of air up between the wicks, and near the top of the chamber is provided a triangular strip, f, between the two intermediate rows of rods, for the purpose of directing the currents of air to and between the spaces in the rows above the wicks.

The working of this chimney is as follows: The drafts of air passing into the bottom and 55 up the chamber are broken and divided by the rods in such a manner that the gases and products of combustion are thoroughly commingled with the air-currents, thereby adding air to the gases so complete as to entirely consume all, and producing an intensely hot blue 60 flame at the chimney-top.

Having described my invention, I claim—

The combination, with oil-stove A, provided with wick-tube casing B, having openings b b and e, and wick-tubes within said casing, of a combustion-chamber, C, communicating with the casing B by the openings e e, and provided with the rods c c above and between the openings e and the wick-tube, as 65 shown and described, and for the purpose set forth. 70

JOHN AENIS.
